N. Anthony Deina

ATTORNEY

UNITED STATES · PATENT OFFICE.

FRANK PARDEE, OF HAZLETON, PENNSYLVANIA.

COAL BREAKER.

Application filed December 30, 1921. Serial No. 525,863.

To all whom it may concern:

Be it known that I, FRANK PARDEE, a citizen of the United States, and resident of Hazleton, Pennsylvania, have invented certain new and useful Improvements in Coal Breakers, of which the following is a specification.

This invention relates to coal breakers and particularly to the construction of cutting rolls used therein.

One object of the invention is to provide means for supporting the lumps, in such a way that they will not fall between the discs of the roll while being carried to breaking position.

Another object is to provide an anvil roll which is composed of a plurality of disc-like members having wide supporting flanges adapted to carry the lumps of coal to the breaking position.

A further object is to provide a pair of co-acting rolls having cutting edges arranged so that lumps of coal will be severed along two different cleavage planes.

Other objects will be apparent from the following specification when read in connection with the accompanying drawings in which—

Fig. 1 is a vertical section showing the cutting rolls of a coal breaker embodying features of the invention;

Fig. 2 is a top plan of a portion of a coal breaker;

Fig. 3 is a diagrammatic section showing a feeding device for delivering the lumps to the breaker;

Fig. 4 is a detail perspective showing the improved form of tooth for the anvil roll having a wide supporting flange formed thereon;

Fig. 5 is a view similar to Fig. 4 showing a tooth of modified construction having a wide cutting edge.

Referring to the drawings the shafts 10 and 12 support respectively the anvil roll 14 and the cutter roll 16, these shafts being carried in suitable bearings 18 and 20 supported by side frames 22. The rolls 14 and 16 are geared together by means of spur gears 24 and 26 and are driven from any suitable source of power, not shown.

The anvil roll 14 is constructed of a plurality of discs 28 which are arranged along side of each other on the shaft 10 and held in proper spaced relationship by means of

separating collars 30. The several discs and collars are secured together by means of longitudinally extending through-bolts 32 and the assemblage is secured to the shaft 10 by a key 34.

Each disc 28 is formed with a number of teeth 36 having cutting edges 38 formed on one extremity thereof. The heel portion 40 of each tooth is formed with oppositely extending flanges 42, as best shown in Fig. 4.

The roll 16 comprises a plurality of discs 44 which are substantially in alignment with the discs 28 of the anvil roll, Fig. 2. The discs 44 are spaced apart by collars 46 and secured to one another by through-bolts 48 and held by a key 50 to the shaft 12. The discs 44 are provided with teeth 52, the ends of which are rounded as at 54 and the heel portions 56 of which are concave in side elevation, Fig. 3. Adjacent the outer end 54 of each tooth the disc is undercut as shown at 58. The teeth 56 are bevelled as at 60 to form comparatively sharp cutting edges 62 which start at the end 54 of the teeth and extend throughout the length of the heels thereof.

The lumps of coal L may be fed to the breaker in any approved manner in so far as the present invention is concerned, but I prefer to feed them in such manner that their greatest length extends substantially in the same direction as the axis of rotation of the rolls. The lumps can be conveniently fed in this manner by means of a spiral feeding device as disclosed in my co-pending application No. 388,462, filed January 12, 1920, and illustrated here diagrammatically in Fig. 3, in which the spiral feeder 64 is mounted to rotate on a horizontal axis above the anvil roll 28 and is rotated so that the lumps L will be deposited on the flanges 42 of the anvil roll, the feeder being provided with long tongues 55 which pass through the spaces 68 between the discs as they rotate.

In Fig. 5 I have shown a slightly modified form of tooth for one of the anvil discs 28 in which the flange 42 on the heel of the tooth is carried around the peripheral end of the tooth in the form of a flange 43 to form a longitudinal cutting edge 39 which is considerably longer than the cutting edge 38 shown in Fig. 4.

In coal breakers of this general type heretofore used the lumps of coal have been fed

to the anvil roll in such a way that they would be apt to straddle two or more of the, comparatively narrow anvil discs. An objection to such an arrangement is that certain of the lumps are very apt to fall down between the adjacent anvil discs so that they are never carried to proper breaking position to be acted upon by the cutting roll. The present invention is intended to provide means for overcoming this objection.

By forming the discs of the anvil roll with longitudinally extending flanges 42, as above described, a wide supporting area is provided to which the lumps of coal can be fed and the discs can be so spaced on the shaft 10 that the space 68 is so arranged as to prevent tipping of pieces which are to be broken. With an anvil roll constructed of discs having the wide supporting flanges it is not necessary that the lumps be fed to the breaker so that they straddle two adjacent discs, as the flanges provide generous support for the individual lumps. In addition there is less likelihood for the lumps to fall endwise between the discs when they are supported on their wide flanges as such flanges present a greater frictional drag on the lumps than that exerted by narrow faced discs heretofore used.

As the lumps are carried down into the bite of the two rolls they are subjected to what may be called a double-breaking action. It is known to those skilled in the art that most coal has at least two cleavage planes along which it can be readily cut or split, these planes being substantially perpendicular to each other. The rolls of this breaker are particularly adapted to take advantage of this inherent quality of the coal. To these ends the discs 44 are provided with the bevelled surfaces 60 forming the cutting edges 62 which are adapted to cut or split the lumps of coal along the axis X, Fig. 2, the lump being held at this time by one of the teeth 40 of the anvil roll. The longitudinal edge 38 is also adapted to cut or split the lump along a plane indicated by the dotted line Y in Fig. 2.

A coal breaker constructed as herein described effectively sizes the coal with a minimum production of fines, the action being of a cutting or splitting nature rather than

a crushing action. The advantages of which will be apparent to those skilled in the art.

Though I have described with great particularity the details of construction of the embodiment herein shown yet it is not to be interpreted that I am limited thereto as structural changes and modifications may be made without departing from the invention as set forth in the appended claims.

What I claim is:

1. In a coal breaker a disc having flanged teeth formed thereon to provide a wide supporting area to prevent the lumps from falling off the face of the disc. 65
2. In a coal breaker a disc having cutter teeth formed with flanges adapted to support and carry the lumps to breaking position. 70
3. In a coal breaker a disc having undercut teeth each tooth having a longitudinal cutting edge at its extremity, the heel portion of each tooth having longitudinal flanges to provide a wide supporting surface 75 for the lumps fed to the breaker. 80
4. In a coal breaker an anvil roll comprising a plurality of discs arranged alongside one another, each disc having flanged teeth adapted to form wide supporting surfaces 85 for the lumps fed to the breaker. 90
5. In a coal breaker a pair of opposed rolls, one of which comprises a plurality of discs having teeth formed with flanges adapted to support the lumps and prevent them from falling between the discs as they are carried to breaking position, the other roll comprising discs having cutting edges which engage the lumps supported on said flanges. 95
6. In a coal breaker a pair of opposed rolls, one of said rolls comprising a plurality of toothed discs having supporting flanges adapted to support the lumps and hold them in proper position so they will not fall between the discs, said discs having longitudinal cutting edges adapted to cut said lumps longitudinally, the other roll comprising a plurality of toothed discs having cutting edges adapted to cut said lumps transversely. 100

In witness whereof, I have hereunto signed my name.

FRANK PARDEE.
